TOGGLE OPERATED PLIERS

Charles H. Orfman, Chardon, Ohio, assignor of one-third
to Ira J. Warner, Cleveland, Ohio
Filed Nov. 16, 1962, Ser. No. 238,102
4 Claims. (Cl. 81—379)

My invention relates to pliers of the pivoted jaw vise grip type, and more particularly to pliers of this type having a movable jaw and a fixed jaw and means associated therewith for normally urging the movable jaw toward the fixed jaw for applying an initial limited pressure on a piece inserted between the jaws, and having means for quickly exerting and releasably locking a subsequent powerful grip on the piece between the jaws. The present invention constitutes an improvement over the structure disclosed in my Patent No. 2,988,941, granted June 20, 1961.

An object of the present invention is to construct a tool such as pliers of the above mentioned type which is of extremely simple construction and yet which, by virtue of such construction, enables the user to grip a piece between the jaws of the tool by application of only a relatively light closing pressure on the handles of the tool whereby the piece is powerfully gripped by the jaws.

A further object of this invention is a tool of the above defined character which is quick acting in the application of a gripping force through the jaws of the tool upon a piece by multiplying an initially relatively light closing force to the handles many times into a positive powerful gripping force to the jaws to securely grip a piece therebetween in a vise-like manner.

Still another object of the invention is the provision of means for selectively and quickly setting the jaws of the pliers to receive a workpiece of selected size and to subsequently, by the manual application of a relatively light closing force on the handles, positively grip and hold the piece in the tool.

A further object of the invention is to provide a relatively simple cam operated means by which to exert a multiplied closing force to the jaws of the tool.

A further object of the invention is the provision of means in a tool of the character described which can be quickly adjusted to apply a vise-like grip to workpieces of different sizes.

A still further object of the invention is the provision of pliers consisting of a minimum number of parts effective to apply a closing force to the jaws of the tool many times that of the initial manual closing force applied to the handles of the tool whereby a piece of selected size may be quickly and positively gripped between the jaws under strong gripping forces.

Other objects and advantages of the invention will become more apparent as the following descriptions of two embodiments thereof progresses, reference being made to the accompanying drawing in which like reference characters are employed to designate like parts throughout the same.

In the drawings:

FIGURE 1 is a side elevation of a tool such as pliers wherein the jaws are shown as in normally closed position but not gripping a piece therebetween, this view eliminating the relative positions of the parts under such conditions;

FIGURE 2 is a view similar to that of FIGURE 1 and illustrates the relative positions of the parts when the pliers grip a piece between the jaws thereof;

FIGURE 3 is a section taken in the direction of the arrows and on line 3—3 of FIGURE 1; and

FIGURE 4 is a fragmentary view illustrating an adjustable dog means.

In carrying out my invention, I provide a handle 1

2

terminating at its forward end in a relatively enlarged fixed jaw portion 2, there being a toothed or serrated jaw element 3 secured therein by means of a rivet 4.

A pivoted handle 5 is pivotally connected by a pin 6 at its forward end to the movable jaw member 7, the movable jaw being pivotally mounted on a center defined by the pin 8. Both the handles 1 and 5 are of channel form in cross section through substantially the entire length. A pressure multiplying member which is in the form of a lever 9 is pivotally mounted at its forward end in the forward end of the movable handle 5 by means of a pin 10 and extends toward the fixed handle 1 and terminates in a portion 11 lying and movable within the channel portion of the handle 1.

15 A coil spring 12 is connected at one end with the movable jaw 7 by having that end of the spring formed to be hooked within an opening 13 in the movable jaw 7 and having its other end hooked into an opening 14 formed in the member 9 thereby tending to normally draw the member 9 and the movable jaw 7 toward each other.

The free end of the member 9, that is, that portion which slides within the channel formation of the rigid handle 1, is formed with a bearing heel 15 along its forward face while the edge 16 is inclined rearwardly away from the bottom of the channel of the handle 1 so as to give clearance as the bearing heel bears against the bottom of the channel in any one of a number of adjusted positions along the channel, as will be pointed out more clearly hereinafter. The spring 12 also exerts a pulling pressure 20 on the member 9 to keep the bearing heel in engagement with the bottom of the channel of the handle 1.

It will be noted from the drawing first in FIGURE 1 that the centers represented by the pins 10, 6 and 8, respectively, are arranged such that the pin 6 lies slightly to the right of a straight line drawn from the centers of pins 10 and 8. This occurs when the jaws are in normal closed position but not engaging a piece therebetween.

Referring to FIGURE 2 in which the jaws of the pliers engage a piece P therebetween, it will be noted that the centers represented by pins 10, 6 and 8 assume a different relative position, that is, the center represented by pin 6 now lies to the left of a straight line drawn through the centers 10 and 8.

The movable jaw member 7 is formed with a workpiece 40 gripping portion 17 which is adapted, in connection with the insert 3, to effectively receive and grip a workpiece P therebetween when the handles are relatively moved toward each other as illustrated in FIGURE 2.

I provide quick adjustable means whereby the pressure multiplying member 9 may be fixed at its end portion 11 in any one of a number of selected positions along the channel of the handle 1.

In FIGURES 1 and 2, one form of such means is illustrated as including bracket 18 preferably formed integrally with the side walls of the channel of handle 1 and projected inwardly in the direction of handle 5. The bracket rotatably carries a cam 19 having cam face 20 extending from and gradually in an upward direction from the low area at 21 to the high area 22. A dog 23 is pivotally mounted at 24 in the handle 1 and is provided with a curved edge 25 for sliding contact with the inclined cam face 20 which, when the cam is rotated in one direction, will move the dog in a counter clockwise direction about the center or pin 24 to engage the dog's pointed nose 26 with the edge 27 of the member 9 under pressure since the heel 15 of the member 9 is in engagement with the bottom of the channel of handle 1 by virtue of the tension of the spring 12, as indicated in FIGURE 2.

A releasable lock for holding the jaws 3 and 17 in tight gripping relation to the workpiece P is shown as comprising a lever 28 pivotally mounted at one end as at 29 on the handle 1 and extending laterally of the pliers to

ward and through a slot 30 in the handle 5. The terminal end 31 of the lever 28 is of reduced width and is formed to overlie that portion of one wall of the handle 5 defining the slot to prevent displacement of the lever therein and to limit the outward movement of the handle 5 as urged by the spring 12 and its tension applied to the pivoted jaw member 7.

The lever 28 is formed with an opening 32 through which the pin 33 fixed in and disposed transversely of the channel of the handle 5 passes. The opening 32 is of elongate form longitudinally of the lever and is characterized by a relatively wide portion 34 defining a ledge 35 against which the pin 33 lies, as in FIGURE 2, when a workpiece is in the jaws 3 and 17, and a relatively narrow portion 36 for receiving the pin as in FIGURE 1 when no workpiece is engaged by the jaws.

In use, the jaws 2 and 7 are readily moved from the position shown in FIGURE 1 to an open position to receive a piece P therebetween, as shown in FIGURE 2, by gripping the handle 1 at its lower end in one hand and the handle 5 in the other hand by pulling on the handle 5 in a direction away from handle 1 to open the jaws. In so doing, and by having the cam 19 turned so that the cam face area adjacent the lowest point, as at 20, is positioned as in FIGURE 1, the dog 23 will lie out of contact with the member 9 thus permitting the end portion 11 of the member to slide along the channel of handle 1 toward the dog. The spring 12 at the same time will pull the member 9 to keep the heel 15 in contact with the bottom wall of the channeled handle 1, as in both FIGURE 1 and FIGURE 2.

As the handles are relatively moved in opposite directions, the handle 5 will swing outwardly about the pin 10, thus drawing the pin 6 connecting the end of handle 5 and the movable jaw 7 from the position in FIGURE 1 to that in FIGURE 2. Thus the pin 6 in the former position lies on one side of a straight imaginary line drawn through the centers of the pins 8 and 10 to the opposite side of such a line as in FIGURE 2.

Since the spring 12 is under initial tension connecting the member 9 with the jaw 7 at a point between and slightly rearwardly of the said imaginary line, relative outward movement of the handles will place the spring under increased tension.

With the jaws separated to receive and grip the piece P as in FIGURE 2, the tension of the spring will tend to close the jaws on the piece with a preliminary gripping force when the handle 5 is released.

The dog 23 is then moved toward the edge 27 of the member 9 until the nose 26 firmly engages the member at this point and this is accomplished by rotating the cam 19 in a counter clockwise direction to bring an upwardly inclined area of the cam face 20 into binding contact with the curved lower edge of the dog 23, as shown in FIGURE 2.

By thus applying a manual closing pressure on the handles, the gripping force of the jaws on the piece is effectively multiplied through the pin 6 connecting the movable jaw 7 with the handle 1. As this pressure is thus multiplied, the handles may be effectively locked in such position as a result of the pin 33 entering and being held in the seat formed between the walls 34 and 35.

To release the grip of the jaws on the piece P, it is merely necessary to shift the lever 28 by thumb pressure on the lip 31 in a rearward direction to unseat the pin 33 from the seat between the walls 34 and 35 and to seat the pin in the seat 36. After the multiplied pressure is released, the cam may be rotated in a reverse direction, thus releasing the pressure of the dog 23 against the member 9.

In FIGURE 4, I have shown a modified form of holding means for the member 9. The dog 40 is supported by a pin 41 operating in laterally aligned slots 42 in the handle 1 side walls, so that the dog is capable of both pivotal and sliding movement along the slots 42. As disclosed in connection with FIGURES 1 and 2, the dog has a

curved edge engageable with the inclined cam surface 20 and as the cam is rotated in a clockwise direction, the dog will be urged about the axis of pin 41 to engage its pointed end 43 with the edge 27 of the member 9. In order to limit undesirable clockwise movement of the dog, I provide a pin 44 carried in transversely aligned ears 45.

Various changes may be made in the details of construction and arrangement of parts of the invention without departing from the spirit thereof or the scope of the appended claims.

I claim:

1. In a tool of the class described, a handle having a relatively fixed jaw, a relatively movable handle, a movable jaw pivotally connected with the movable handle and fixed jaw, means pivotally carried at one end on the movable handle for sliding engagement at its other end with the other handle when the handles are moved toward and away from each other, tension means connecting said movable jaw with said first means tending normally to urge the jaws toward closed position, means limiting the sliding movement of the first means with respect to said other handle when a workpiece is gripped between the jaws, said slide limiting means comprising a member pivotally supported in said other handle for engagement with said first means, and adjustable means on said other handle for engagement with said member while said member is in engagement with said first means to thereby prevent further sliding movement of the first means with respect to the said other handle as the jaws are brought into final gripping relation to a workpiece.

2. In a tool of the class described, a handle having a relatively fixed jaw, a relatively movable handle, a movable jaw pivotally connected with the movable handle and fixed jaw, means pivotally carried at one end on the movable handle for sliding engagement at its other end with the other handle when the handles are moved toward and away from each other, tension means connecting said movable jaw with said first means tending normally to urge the jaws toward closed position, cam means limiting the sliding movement of the first means with respect to said other handle when a workpiece is gripped between the jaws, said slide limiting means comprising a member pivotally supported in said other handle for engagement with said first means, and adjustable means on said other handle for engagement with said member while said member is in engagement with said first means to thereby prevent further sliding movement of the first means with respect to the said other handle as the jaws are brought into final gripping relation to a workpiece.

3. In a tool of the class described, a handle having a relatively fixed jaw, a relatively movable handle, a movable jaw pivotally connected with the movable handle and fixed jaw, means pivotally carried at one end on the movable handle for sliding engagement at its other end with the other handle when the handles are moved toward and away from each other, tension means connecting said movable jaw with said first means tending normally to urge the jaws toward closed position, cam means limiting the sliding movement of the first means with respect to said other handle when a workpiece is gripped between the jaws, said slide limiting means comprising a member pivotally and slidably supported in said other handle for engagement with said first means, and adjustable means on said other handle for engagement with said member while said member is in engagement with said first means to thereby prevent further sliding movement of the first means with respect to the said other handle as the jaws are brought into final gripping relation to a workpiece.

4. In a tool of the class described, a handle having a relatively fixed jaw, a relatively movable handle, a movable jaw pivotally connected with the movable handle and fixed jaw, means pivotally carried at one end on the movable handle for sliding engagement at its other end with the other handle when the handles are moved to-

ward and away from each other, tension means connecting said movable jaw with said first means tending normally to urge the jaws toward closed position, cam means limiting the sliding movement of the first means with respect to said other handle when a workpiece is gripped between the jaws, said slide limiting means comprising a member pivotally supported in said other handle for engagement with said first means, and adjustable means on said other handle for engagement with said member while said member is in engagement with said first means to thereby prevent further sliding movement of the first means with respect to the said other handle as the jaws are brought into final gripping relation to a workpiece, one of the pivotal axes of the movable jaw being shiftable to one side or the other of a straight line passing through the other pivotal axis of the movable jaw and the pivotal

axis of said first means on said movable handle to open the jaws to receive the workpiece therebetween and in a reverse direction as the handles are moved to grip a workpiece in the jaws to impose a multiplied gripping effort on the workpiece.
